(No Model.)

W. J. JONES.
ADJUSTABLE WRENCH.

No. 587,972.

Patented Aug. 10, 1897.

UNITED STATES PATENT OFFICE.

WILLIAM J. JONES, OF MCKEESPORT, PENNSYLVANIA.

ADJUSTABLE WRENCH.

SPECIFICATION forming part of Letters Patent No. 587,972, dated August 10, 1897.

Application filed June 1, 1897. Serial No. 639,065. (No model.)

To all whom it may concern:

Be it known that I, WILLIAM J. JONES, a citizen of the United States of America, residing at McKeesport, in the county of Allegheny 5 and State of Pennsylvania, have invented certain new and useful Improvements in Adjustable Ratchet-Wrenches, of which the following is a specification, reference being had therein to the accompanying drawings.

10 This invention relates to certain new and useful improvements in ratchet-wrenches, and has for its object to provide a wrench of this type which may be made adjustable, so as to conform to any sized nut or bolt upon 15 which it may be desired to use the same.

The invention consists, briefly, in a die or disk having adjustable jaws adapted to operate thereon and independent means within the die for adjusting said jaws, together with 20 pivoted levers arranged in the handle in a manner to have one of the levers in engagement with the ratchet and the other lever out of engagement therewith, as desired; and to this end the invention consists in the novel 25 construction, combination, and arrangement of parts to be hereinafter more specifically described, and particularly pointed out in the claims.

In describing the invention in detail reference is had to the accompanying drawings, 30 forming a part of this specification, and wherein like letters of reference indicate similar parts throughout the several views, in which—

Figure 1 is a front view of the wrench and 35 a portion of the handle, partly broken away to show the manner in which the adjustable jaws are secured in the die, also showing the handle, partly broken away, with one of the ratchet-levers secured to engage the ratchet 40 and the other released, so as to be out of engagement therewith. Fig. 2 is a longitudinal sectional view of the wrench and a portion of the handle, showing a portion of a bolt in engagement with the adjustable jaws. Fig. 3 is 45 a longitudinal sectional view taken on the line X X of Fig. 2. Fig. 4 is a vertical sectional view of the die, taken on the line Y Y of Fig. 2, showing the jaws holding the nut or bolt-head. Fig. 5 is a side view of the die with 50 the adjustable jaw in position and the screw removed. Fig. 6 is a transverse vertical sectional view of the die. Fig. 7 is a perspective

view of one of the adjustable jaws. Fig. 8 is a plan view of one of the screws supporting said jaws. Fig. 9 is an underneath plan view 55 of a portion of a toothed ring employed for adjusting the jaws.

Referring now to the drawings by reference-letters, *a* represents the shell, which has formed integral therewith a ratchet *b*. A 60 shoulder *c* is formed on the back of said shell and is adapted to receive the handle *d*, which fits over the ratchet and is provided with recessed portions *e*, in which are pivotally secured the ratchet-levers *f*, which are held in engagement with the ratchet by means of springs *g* and abutting against the same, secured to the body portion of the handle *d*, and when desired are held out of engagement with the ratchet by means of lugs *h*, which are pivotally attached to the body portion of the handle, said lug consisting of a plate pivotally 65 secured to the handle in any suitable manner and adapted to be rotated so as to engage the end of the lever and hold the same out of 70 engagement with the ratchet-wheel. The said handle is held in position by means of a collar *k*, which fastens by screws or other suitable means to the die *b*, said collar and die being provided with a central aperture to permit 75 the bolt or other device being held to pass 80 through the same.

Secured to the inner face of the shell by screws or other suitable means is a die *l*, which is provided with cut-away portions *m*, in 85 which the adjustable jaws *n* operate. These jaws *n* are provided with suitable beveled flanges *o*, which slide in grooves provided therefor in the die, said jaws being supported by means of screws *p*, the head *q* of which engages in the recesses provided therefor in the rim of the shell, the shank *r* of said screw between the head proper and the screw *p* being milled to receive the toothed ring *s*, which operates in the groove *t*, provided on the face of 95 the die, and is held in position by means of the ring *u*, engaging the outer face of said milled ring *s* and secured by screws *v* or other suitable means to the die or rim of the shell.

The operation of my improved adjustable 100 wrench is as follows: Assuming that the jaws have been engaged against the head of the bolt, as is shown in Figs. 2 and 4, and it is desired to release the same, the milled ring *s* is

turned, which causes the same to engage the milled portion *r* of the screws carrying adjustable jaws, thus turning the same and withdrawing the jaws from their engagement with the head of the bolt, when the same may be readily removed. When it is desired to apply the wrench to a nut, bolt-head, or the like, the adjustable jaws are moved outward sufficiently to admit the object which it is desired to clamp, when the ratchet-lever *f* is released from its holding-lug *h*, the spring *g* forcing the outer end of the said lever outward from the handle and the inner end of the same into engagement with the ratchet, when by giving the handle an upward and downward movement this lever engages the teeth of the ratchet to bring the jaws firmly into engagement with the object to be held and permitting the turning of the same.

It will be noted that various changes may be made in the details of construction without departing from the general spirit of my invention.

Having fully described my invention, what I claim as new, and desire to secure by Letters Patent, is—

1. In an adjustable wrench, consisting of a

shell having a ratchet formed integral therewith, a handle engaging over the ratchet secured to said shell, ratchet-levers arranged in the handle to operate the ratchet, a die secured in said shell, adjustable jaws operating in said die, and means for adjusting said jaws radially within the die, substantially as shown and described.

2. A ratchet-wrench consisting of a die, jaws arranged in said die, and means for adjusting said jaws, a shell surrounding the die and jaws, a ratchet formed with said shell, a handle secured thereto, and ratchet-levers operating in said handle to engage the ratchet.

3. A ratchet-wrench consisting of a shell, and a die secured therein, a ratchet formed on said shell, jaws operating in said die, means for adjusting said jaws, and means within the handle for operating the ratchet, substantially as shown and described.

In testimony whereof I affix my signature in presence of two witnesses.

WILLIAM J. JONES.
